(57) **CLAIM**

I claim the ornamental design for a cooler, as shown and described.

DESCRIPTION

FIG. 1 is a perspective view of a cooler, showing my new design;

FIG. 2 is a right side elevation view of the cooler;

FIG. 3 is a front elevation view of the cooler;

FIG. 4 is a left side elevation view of the cooler;

FIG. 5 is a rear elevation view of the cooler;

FIG. 6 is a top plan view of the cooler; and,

FIG. 7 is a bottom plan view of the cooler.

The broken lines in the figures illustrate the portions of the cooler and form no part of the claimed design.

The evenly spaced longer dashed broken lines below the zipper portion of the cooler in the drawings depict unclaimed stitching lines of the cooler.
